Related U.S. Application Data

The ornamental design for a modular heavy-duty grab rail, as shown and described.

(62) Division of application No. 29/283,882, filed on Aug. 27, 2007, now Pat. No. Des. 591,427.

DESCRIPTION

(30) **Foreign Application Priority Data**

Mar. 15, 2007 (EP) 000692249

FIG. 1 is a perspective view of a modular heavy-duty grab rail, showing our new design;

(51) **LOC (9) Cl.** **25-02**

FIG. 2 is an elevational view from one end of an end mounting bracket of the modular heavy-duty grab rail, as shown in FIG. 1;

(52) **U.S. Cl.** **D25/41**

FIG. 3 is a perspective view of the end mounting bracket shown in FIG. 2;

(58) **Field of Classification Search** D25/41, D25/38; D6/533; 256/17, 59; 182/113, 182/206

FIG. 4 is a perspective view of the rail of the new design of modular heavy-duty grab rail; and,

See application file for complete search history.

FIG. 5 is a perspective view of a cover for the flange of each mounting bracket.
